R. M. CRUM

FLAGPOLE

Filed Sept. 3, 1925

Rufus M. Crum
BY
INVENTOR.

H. G. Charles
ATTORNEY.

UNITED STATES PATENT OFFICE.

RUFUS M. CRUM, OF WICHITA, KANSAS.

FLAGPOLE.

Application filed September 3, 1925. Serial No. 54,330.

To all whom it may concern:

Be it known that I, RUFUS M. CRUM, a citizen of the United States, residing in the city of Wichita, county of Sedgwick, and 5 State of Kansas, have invented certain new and useful Improvements in Flagpoles, reference being had to the accompanying drawings, forming a part of this application.

My invention relates to flag poles, the objects of which are as follows;

First; to provide a flag pole having a pivotedly connected joint near the base thereof.

Second; a flag pole having adjustable 15 means longitudinally.

Third; to provide a flag pole having adjustable hanging means for the flag.

Fourth; to provide a flag pole with a counter-balance on the lower end for convenience of manipulating the swing thereof 20 when attaching or detaching a flag.

In the drawings, like figures will apply to like parts in the several views.

Referring to the drawings:

Fig. 1 is an elevation of the pole supported 25 by a concrete base.

Fig. 2 is an enlarged detailed drawing showing the supporting features of the pole in its base member.

Fig. 3 is a transverse view of Fig. 2, parts removed for convenience of illustration.

Fig. 4 is a top view of the base member and a sectional view of the pole centrally positioned therein.

Fig. 5 is a fragmentary view of the top of the pole, flag supporting collar being in section.

Fig. 6 is a top view of Fig. 5.

The following is a complete description 40 of the construction and intent of my newly invented flag pole.

In Fig. 1, 1 is a concrete base imbedded in the earth functioning as a bearing for the base of the pole but I do not confine the invention to this means of support alone as the base thereof may be attached to buildings or other structures.

The base member 2 consists of a metal 50 tubing being split and expanded, and the sides 3 thereof being parallel to receive the hanging means hereinafter described. 3' are strips of metal firmly riveted to the sides and extending longitudinal, functioning as re-enforcing means. At the top end of the base member I have cut the side away at A

so that the pole being pivoted as at 4 will turn as shown by dotted lines B until the top will descend near the ground for convenience of attaching a flag, banner or the like placed on fabric.

The member 5 is supported by a clamp comprising members 6 and 6'. The said members being clamped together by means of cap screws 7, the said clamp member 6 being arcuated is adapted to seat in the shell 60 of the base member as at C; and the adjacent member 6' functions as the pivot bearing which is accomplished by means of cap screws 8 passing through perforations in the shell of the base member and the re-enforcing strips, and firmly engaging in the said member 6' as shown in Fig. 4.

In the said member 6' I have placed a set screw 9 as further means for preventing the pole member 5 from sliding downward 75 through the clamp. On the extreme bottom end of the pole member 5 I have placed a collar 10 which engages snugly between the re-enforcing strips 3' and brought to engagement with the shell of the base member 80 by means of a bolt 11 engaging through said collar and the end of the pole engaging therein and passing through an aperture in the shell as at D; then by placing nut 11' on the protruding end of said bolt 11 the 85 pivoted portion of the pole is held firmly in axial alignment with the base thereof.

The pole extension 12 which is firmly attached to the pole member 5 as at E functions as the top member of the pole to which the flag is attached; and near the top end thereof I have provided collars 13 slidably engaging thereon and attached firmly thereto when properly stationed by means of set screws 14, by which means it is convenient 90 to place a flag at half mast when appropriate. In the periphery of the collar 13 is a groove adapted to receive a ring 15, the said ring having a loop therein forming an eye 16 by which means a hook or cord supporting the flag may be attached thereto.

In Fig. 5 the said collar and ring are shown in section taken on line F looking in the direction of the arrows. It will be understood that the base member 5 may be 105 filled with lead or other weight material between the pivot point 4 and the lower end thereof functioning as a counter-balance for the upper portion of the pole.

It will be understood that various lengths 110

may be employed for the base member to agree with the various heights of poles; and a greater number of sections may be assembled than that shown in drawings and such 5 modifications may be employed as lies within the scope of the appended claims, and having fully described my invention, what I claim as new and desire to secure by Letters Patent is:—

- 10 1. In a flag pole, a base member of metal tubing, a split longitudinally in the side thereof, and the said split being separated equal to the inside diameter of said tubing, a clamp in the top end of said base member, 15 the said clamp being pivotally attached thereto, a pole positioned in said clamp so that the lower end thereof will extend downward engaging in said split opening for axial alignment with said base member, a 20 collar attached to the lower end of said pole, said collar equaling the inside space of said base member for snug engagement, and a bolt-through said collar and pole, the said

bolt engaging through an aperture in the shell of said base member as rigid attaching means of the base of said pole to the said base member, adjustable means on the top end of said pole for suspending a flag. 25

2. In a flag pole, a tubular base supporting member, said member having an opening 30 in the side thereof, a notch in the top end of said member, the said notch functioning as a support, a flag pole positioned in the opening of said base support, the said pole being pivotally connected to the top end of said 35 support and adapted to swing laterally, resting in said notch, an annular collar on the lower end of said pole, said collar functioning as a counter-balance and spacing means for the axial alignment of said pole to said 40 base, an anchor bolt radially passing through said collar and said pole, an aperture through the wall of said base, the said bolt engaging through said aperture as anchoring means for said pole.

RUFUS M. CRUM.
